UNITED STATES PATENT OFFICE

WILLIAM R. MOOREHEAD, OF BRONSON, MICHIGAN, ASSIGNOR TO L. A. DARLING COMPANY, OF BRONSON, MICHIGAN, A CORPORATION OF MICHIGAN

DESIGN FOR A DISPLAY-STAND BASE

Application filed February 5, 1931. Serial No. 38,563. Term of patent 14 years.

To all whom it may concern:

Be it known that I, WILLIAM R. MOOREHEAD, a citizen of the United States, and resident of Bronson, county of Branch, State of Michigan, have invented a new, original, and ornamental Design for a Display-Stand Base, of which the following is a specification, reference being had to the accompanying drawing, forming a part thereof.

The figure is a top perspective view of a display-stand base showing my new design.

I claim:

The ornamental design for a display-stand base, substantially as shown.

In testimony whereof I have hereunto signed my name to this specification.

WILLIAM R. MOOREHEAD.
